ABSTRACT OF THE DISCLOSURE

A batch drier for grain is disclosed which includes an annular drying chamber into which grain is fed for drying and subsequently removed. Surrounding the chamber is an external enclosure with a duct located radially inwardly of the drying chamber through which drying and cooling air is drawn. Automatic control means regulates the loading, drying and unloading operations according to a predetermined sequence.

This invention relates to a batch drier for grain and similar commodities, that is to say a drier which operates on batches of the commodity in turn rather than one which acts continuously to dry a commodity moving in a continuous path.

According to the present invention a batch dried includes means for automatically loading the drier, drying the grain, and unloading the drier, in a drying cycle, and for automatically re-cycling. The drying cycle may also include the step of automatically cooling the dried grain before unloading.

The automatic initiation of a new cycle when the grain has been unloaded from the drier following a preceding cycle enables batch drying to be carried out continuously without the necessity of having an operator looking after the machine all the time.

There could be one or two timing clocks which can be set respectively to a convenient drying time and a convenient cooling time, but as an alternative a device sensitive to the wetness of the grain and a device sensitive to the temperature of the grain could be used to indicate when drying is complete and when cooling has been achieved respectively.

Automatically operated filling mechanism for filling the drying compartment from a supply of grain could operate in association with a switch at the top of the drying compartment for indicating when the compartment is full and switching off the filling mechanism. Similarly automatically operating emptying mechanism could be associated with a switch which operates when the compartment is empty to switch off the emptying mechanism.

The drier itself conveniently operates by radially inward flow of drying air or cooling air through the grain and this flow of air is conveniently achieved by suction from within the grain compartment rather than by blowing from without.

Thus in a preferred form of the drier the drying chamber is generally of annular form whether horizontal or vertical and the air is drawn radially inwards through the perforated walls of the annular chamber into a central area under the influence of a fan providing the necessary suction.

It is preferred that there is an external enclosure defining an air chamber around the annular drying chamber so that the drier can be totally enclosed. This chamber which acts to distribute the air around the drying chamber would be associated with a heater for raising the air to the appropriate temperature.

The invention may be carried into practice in various ways and one embodiment will now be described by way

2

of example with reference to the accompanying drawings of which:

FIGURE 1 is a sketch showing the general arrangement of a batch drier housing embodying the invention; and

FIGURE 2 is a circuit diagram of the control system.

The compartment for each batch of grain to be dried is of generally annular constant cross-section along a horizontal axis and may be defined as the space between expanded metal inner and outer hexagonal shaped casings 11 and 12, and closed ends. Grain is fed into the compartment from a hopper 13 at one end by means of a screw feed 14 driven by an electric motor for taking the grain from the hopper towards the other end of the casing. A fan 15 at one end of the interior of the inner casing 11 draws drying or cooling air through the grain in generally radial directions from an enclosure surrounding the outer hexagonal casing 12. This enclosure 16 defines a distribution space for the air which enters at the lower part of one end of the enclosure through a chamber 17 by way of a burner 18 which might burn gas or oil, or might be electric.

The batch drier is thus enclosed and operates by radially inwardly flowing hot air through the grain. At the lower part of the grain compartment between the casings 11 and 12 a second screw feed 19 is used for removing a batch of dried grain in preparation for receipt of the next wet batch at the top and this feed 19 is also driven by an electric motor.

The relays for switching the motors on and off are shown at A and C in the control circuit of FIGURE 2, the relay A being for the motor for the feed 14 for supplying moist grain and the relay C being for the motor driving the feed 19 for removing the dried grain.

FIGURE 1 also shows a top pressure switch H mounted at the far end of the feed 14 which operates to close an electric contact in the circuit of FIGURE 2 when the grain rises sufficiently indicating that the drying chamber is full. Similarly there is a bottom pressure switch J which also has a contact in the control circuit which is closed about half way through the filling operation and which opens again when all the grain has been removed and the drier is ready for the next batch of wet grain.

The automatic recycling operation of the batch drier will be understood best from the description of operation of the control circuit in FIGURE 2.

T_1 and T_2 are clocks which can be pre-set to any desired time interval and which each have two contacts which close in turn with an interval of about five minutes, the first one closing after the clock has run for the pre-set time. The clocks run as long as an electrical supply is maintained through their motors; both contacts of a clock return to the normal positions when the electrical supply is removed from an energising winding F associated with that clock. The clocks are then ready for a new cycle when the windings F are again energised. It is to be noted that the clocks "remember" the pre-set time from cycle to cycle and do not have to be set each time as with an "egg-timer" type of clock.

The burner 18 in FIGURE 1 has a control shown at E in FIGURE 2 and this control includes a circuit for energizing a lock-out relay D whenever a photo-electric device detects that the burner has gone out and the air is no longer being heated. For the purposes of this description it is sufficient to say that the burner operates whenever there is an external connection between the terminals marked 8 and 6 on the control E.

As has been described above the relays A and C are for operating the loading and unloading motors driving the feeds 14 and 19, while the relay B is used to switch on the fan 15 for inducing the flow of hot and cold air through

the grain. T_4 is a hand operated clock which can be set to prevent refilling of the drier after a set time, perhaps because the supply of grain will be exhausted by that time or because only a certain number of loads are to be dried.

The operation of drying a batch may be summarised as follows. After filling the drying compartment the grain is dried for about 2 hours using air at a temperature of about 140° F. This is followed by drawing cooling air through the grain but with the burner not operating, for 15 to 20 minutes after which the unloading feed starts to empty the drier at the end of that cycle. It should be explained that these temperatures and times are examples suitable for particular grain in a particular state and experience will determine the setting in a particular case.

The operation of the automatic control system will now be described and it is believed that the nature of the control circuit shown in FIGURE 2 will become apparent from this description without its being first described in detail.

It will be noticed that at starting the switches H and J will be in the open position shown in FIGURE 2 so that there will be no supply to the relay B for energising the fan motor and no supply to the energising windings F of the clocks T_1 and T_2 and also no supply to the relay C for the unloading motor.

Initiation of automatic operation is by hand operation of three switches W, X, and Y so that the contacts W_2 , X_3 , Y_1 in series are all closed to connect the control circuit supply from the main line L_3 to the contacts of the switches H and J and to the relay A of the loading motor through the normally-closed contacts T_4 , T_1 , B_1 and C_1 . In consequence the main switch S_A for the loading motor is closed to start the loading motor so that the grain is fed from the hopper 13 through the loading feed 14 into the drying compartment.

Closing of the switch W_2 ensures that a switch W_1 for hand operation of the loading motor remains open, and similarly, closing of the switch contacts X_3 and Y_1 ensures that contacts X_2 and Y_2 remain open to prevent hand operation of the fan motor and the unloading motor. A contact X_1 closes at the same time to enable the fan motor relay B to be energised when the supply becomes available.

Once the relay A has operated, its contact A_2 closes to short circuit the normally closed contact T_4 of the clock T_4 . Thus the clock can only prevent starting of a filling operation and cannot stop it once it has started. Its contact can also be shorted by a hand-operated contact V. Also the contact A_3 opens to ensure that the relay C for the unloading motor cannot become energised when the switch J closes.

Loading continues until when the drier is about half full of grain the switch J closes to provide the energising supply to the winding F of the clock T_1 . However, the relay C is not energised because the contact A_3 is open.

Eventually when the drier is full, the switch H closes to energise the winding F of the clock T_2 and in fact to start the clock motor through the normally closed contacts T_1 No. 2, T_2 No. 2 and D_1 . The supply voltage is also supplied through the contacts T_1 No. 2 and X_1 to energise the relay B for the fan motor and in consequence the fan motor switch S_B closes. The contact B_1 opens to de-energise the relay A so that the loading motor stops and the contact B_2 closes to maintain the supply across the relay B in spite of any opening of the switch H for example due to the grain level falling as the grain is dried. The contact B_3 opens to maintain the relay C de-energised in spite of closing of the relay contact A_3 and the contact B_4 closes to provide the supply for the burner 11 which ignites, provided a manual switch Z has been closed, so that the hot air is delivered to the fan through the grain in the drying chamber. This state of affairs continues until the time of about two hours set on the clock T_2 has expired. It should be noted that if the flame goes out accidentally the photoelectric detector will energise the relay

D so that the contact D_1 will open and stop the motor of the clock T_2 until re-ignition has occurred.

At the end of the time set on the clock T_2 the contact 5 T_2 No. 1 opens to switch off the burner 11 so that the air drawn through the grain by the fan 15 ceases to be heated and can now be used to cool the grain. Five minutes after this the contact T_2 No. 2 changes over to start the motor of the clock T_1 which is set to the desired cooling time.

The fan continues to run until at the end of the cooling time the contact T_1 No. 1 opens (to prevent subsequent 10 energisation of the relay A when the relay B is released) and five minutes after this the contact T_1 No. 2 opens to remove the supply from the relay B and stop the fan and to remove the energising supply from the winding F of the clock T_2 so that the contacts T_2 Nos. 1 and 2 switch 15 back to the positions shown in FIGURE 2. Release of the relay B causes the contact B_1 to close although the relay A is not re-energised because the contact T_1 No. 1 is now open. The contact B_2 opens and also the contact B_4 to prevent re-ignition of the burner 11 in consequence 20 of the closing of the contact T_2 No. 1.

Also the contact B_3 closes so that now the relay C is energised through the switch J and the contacts A_3 and B_3 . This starts the unloading motor through its 25 main switch S_C and the dried and cooled grain is unloaded from the drier until when it is empty the switch J switches back to the position shown in FIGURE 2 and the relay C is released. During operation of the unloading motor the contact C_1 is open to prevent re-energisation 30 of the relay A and when the switch J opens the energising supply is removed from the winding F of the clock T_1 , so that its contacts T_1 No. 1 and T_1 No. 2 are in the position shown in FIGURE 2 in preparation for the next cycle which begins again automatically as soon 35 as the contacts T_1 No. 1, B_1 and C_1 are all once again closed.

Each of the main switches S_A , S_B and S_C has an overload coil in each phase capable of operating an overload trip which in the conventional use of a direct-on-line 40 starter would operate to open a contact in the circuit of the operating relay A, B or C. However, in the present circuit the overload trip contacts SA_1 , SB_1 , SC_1 , are connected in series in the supply to the control circuit so that if any one of the motors is overloaded the control circuit is de-energised and everything shuts down.

In practice one can estimate from experience the control time to be allowed for drying and cooling but in a modification either of the clocks T_2 and T_1 can be dispensed with by using devices respectively sensitive to the 45 wetness of the grain and the temperature of the grain. Thus instead of having the clock T_2 one could have a wetness device which would detect when the grain was dried and operate contacts equivalent to the contacts T_2 No. 1 and T_2 No. 2 and in the same way a temperature device could be used instead of the clock T_1 having 50 contacts which open when the grain is cooled after the drying operation.

Such a device might measure repeatedly the wetness of small samples of the grain until a measurement 55 showed that the grain was sufficiently dry. In order to avoid a false reading due to a small random sample being drier than the bulk of the grain, it could be arranged that a dryness reading must be repeated or must persist for some minutes before the drying operation is concluded.

The filling and emptying arrangements could each be at either end of the drier, and of course the disposition and operation of the switches H and J will depend upon the arrangement chosen.

What I claim as my invention and desire to secure by 70 Letters Patent is:

1. A batch drier for grain comprising a drying chamber of annular form, means for loading grain into said chamber, means for emptying grain from said chamber, an external enclosure defining a distribution space for air 75

around the chamber, a duct radially inwardly of the drying chamber, means for drawing drying and cooling air radially inwardly through the duct from the distribution space, and automatic cycling means for controlling the loading and emptying means and the means for drawing air in a predetermined sequence including the steps of loading, drying, unloading and recycling said steps.

2. A batch drier as claimed in claim 1 including means for automatically cooling the dried grain before unloading.

3. A batch drier as claimed in claim 1 including a timing clock which can be set to a repeatable predetermined drying time.

4. A batch drier as claimed in claim 1 including a device sensitive to the wetness of the grain for controlling termination of the drying step.

5. A batch drier as claimed in claim 1 including a device sensitive to the temperature of the grain for controlling a step in the cycle.

6. A batch drier as claimed in claim 2 including a device sensitive to the temperature of the grain for controlling the termination of the cooling step.

7. A batch drier as claimed in claim 1 including a switch at the top of the drying chamber responsive when the compartment is full to switch off the loading means.

8. A batch drier as claimed in claim 1 including a switch responsive when the drying compartment is empty to switch off the emptying means.

9. A batch drier as claimed in claim 1 wherein said means for drawing air comprises a fan located in a region radially within the drying chamber.

5 10. A batch drier as claimed in claim 1 including means for rendering the loading device inoperative after a drying step has started and before the unloading step has ended.

11. A batch drier as claimed in claim 1 in which the drying chamber has perforated walls.

12. A batch drier as claimed in claim 11 including inner and outer perforated walls defining the drying chamber, the radius of the inner perforated wall from the axis of the chamber being greater than the radial distance between the inner and outer walls.

13. A batch drier as claimed in claim 1 including a heater for raising the drying and cooling air to a predetermined temperature.
